UNITED STATES PATENT OFFICE.

BENNETT KAMINSKY, OF PITTSBURGH, PENNSYLVANIA.

WATER-FOUNTAIN.

1,128,001.

Specification of Letters Patent.

Patented Feb. 9, 1915.

Application filed April 30, 1912. Serial No. 694,090.

To all whom it may concern:

Be it known that I, BENNETT KAMINSKY, a citizen of the United States of America, residing at Pittsburgh, in the county of 5 Allegheny and State of Pennsylvania, have invented certain new and useful Improvements in Water-Fountains, of which the following is a specification, reference being had therein to the accompanying drawing.

10 This is an improvement upon my Patent Number 13,195, reissued January 10, 1911, for certain improvements in water fountains.

15 Besides having the same objects in view as disclosed in my prior patent above referred to, the present invention aims to provide a sanitary drinking fountain possessing certain qualifications that are essential from a sanitary, manufacturing and commercial 20 standpoint.

First, the construction of the fountain prevents the lips of a person drinking from coming in contact with the fountain. Second, water that has touched the lips of a 25 person drinking does not come in contact with the water outlet or orifices again. Third, the consumption of water is considerably reduced by reason of the pressure of water being regulated to provide a constant 30 discharge without splashing or spraying. Fourth, a fountain that has the water outlet or orifices thereof provided with shields or closures that are open only when water is flowing. The shields or closures prevent 35 foreign matter from entering the outlet openings, either accidentally or by reason of maliciously inclined or unscrupulous persons placing matter in openings of the fountain. Fifth, a fountain having associated 40 with the water outlets or discharge orifices thereof shields which not only prevent foreign matter from entering said outlets or orifices but further provide means whereby the outer termini of said orifices or outlets 45 can be cleansed due to the manner in which the shields can be positioned with respect to the outlets or orifices. Sixth, to accomplish the above results by a mechanical construction that is simple, durable, inexpensive 50 to manufacture, easy to install, and highly efficient for the purposes for which it is intended.

With the above and other objects in view, the invention resides in the novel construction, combination and arrangement of parts 55

to be hereinafter specifically described and then claimed.

References will now be had to the drawing, wherein:

Figure 1 is a side elevation of a fountain 60 in accordance with this invention. Fig. 2 is a plan of the same, and Figs. 3 to 6 inclusive are diagrammatic views illustrating the projection of streams of water to form a body that is momentarily suspended in the 65 air for drinking purposes.

The reference numeral 1 denotes a water supply pipe provided with a globular valve 2 that has a valve stem 3 provided with a crank or handle 4 whereby the passage of 70 water through the valve 2 can be easily controlled. In other words, the water can be shut off or turned on. Connected to the valve 2 is a coupling or a stand pipe 5 provided with a head 6 in which is located a 75 pressure regulator 7 that can be adjusted to control or regulate the discharge or passage of water from said head. In communication with the head 6 are oppositely disposed curved tubular arms 8 that extend upwardly 80 above the plane of the head 6, said arms having the upper ends thereof provided with nozzles 9 in the form of casings that are disposed at an angle, the inner walls of said nozzles having discharge openings or 85 orifices 10.

Each nozzle has a shield or closure 11 adapted to cover and close the discharge openings 10 when the water is not flowing through said nozzles. The shields 11 are 90 pivotally supported relatively to the nozzles 9 whereby said shields or closures can be opened or closed. This operation is performed simultaneous with the turning on and off of the water supply. The outer ends 95 of the shields are pivotally connected, as at 12 to connecting rods 13, said rods having the ends thereof pivotally connected, as at 14 to the ends of a cross head 15, carried by the valve stem 3 and movable in unison 100 therewith.

In order that the shields or closures can be simultaneously opened or closed, it is necessary that one of the shields, for instance at the left hand side of Fig. 1, be 105 pivotally supported in proximity to the nozzles, as at 16 and the connecting rods 13 connected to the extreme end of the shield. The other shield is pivotally supported, as at 17 by a bracket 18 forming part of the 110

nozzle. The connecting rods 13 associated with the other shield is connected intermediate the ends of said shield. In this manner both of the shields will be opened 5 or closed when the valve stem 3 is turned.

The connecting rods 13 are curved, as best shown in Fig. 2, whereby the cross head 15, which is offset relatively to the nozzles 9, will actuate the shields 11 when the valve 10 stem 3 is moved. As illustrated in Fig. 1, the nozzles 9 are angularly disposed whereby water projected from the discharge opening or orifices 10 will travel in a direction and to a point directly above the head 6.

15 The impact of the streams of water is sufficient to produce a flat elongated body of water that is momentarily suspended in the air. Only sufficient force is necessary to cause the streams to reach the central point 20 and permit them to merge into each other without causing any splash or spray. It is in this connection, that the present invention differentiates from that disclosed in my prior patent where it was necessary to 25 use a pressure of water that would produce a jet to be thrown vertical, the jet being in the form of a small geyser from which a person could readily obtain water.

In the present invention the comingling of 30 the two oppositely disposed streams is sufficient to form a body of water that can be easily drunk without any danger of wasted water again contacting or passing through the nozzles.

35 By reference to Fig. 3 it will be observed that the nozzles 9 are disposed and the outlet openings thereof so arranged that the streams of water will intersect at a central point. In Fig. 4 the same results are obtained, but the openings are so arranged 40 that the streams of water will converge and meet at points separated from each other, the streams eventually merging into a body of water.

45 In Fig. 5 of the drawing the discharge openings are so arranged that the streams from one nozzle will intersect the streams from the other nozzle and meet at points that are separated and thereby provide a 50 large water surface that permits of a person easily obtaining a drink.

In Fig. 6 of the drawing each nozzle has a single discharge opening.

I desire to call attention to the fact that 55 the discharge openings or orifices of the nozzles 9 are washed by the action of the shields or closures 11 each and every time the fountain is used. For instance, when used in connection with large schools or in 60 public drinking places, it is necessary for a person to turn on the water and thereby open the shields or closures 11 before partaking of water. The shields or closures 11 are also utilized to provide means to cause 65 the washing of the outer terminus of each

nozzle, either when the shield is shifted toward or away from the nozzle. It will be assumed that the shields are brought in close proximity to the nozzles, but not entirely closing them and when in such position, as 70 the water supply is partially open, the water as it passes out through the nozzles will impact against the shields and be thrown back to cleanse, flush or wash the outer ends of the nozzles. Such operation is continued 75 until the water is entirely cut off. It will be assumed that the shields are in closed position. If the water supply is open and the shields not shifted to entirely clear the outlets, the water as it passes from the outlets 80 will impact against the shields and be thrown back to cleanse, flush or wash the nozzles. It is obvious that the pressure of water in the nozzles 9 can be regulated 85 whereby the streams projected from said nozzles will be of sufficient volume to produce a body of water for drinking purposes.

It is thought that the operation and utility of the fountain will be apparent without further description, and I reserve the right to use the plurality of said nozzles 9, to arrange the same at any desired angle or position, to make the nozzles various shapes and sizes, and to use a treadle or other 95 means than the hand operated means herein shown for turning off and on the water and simultaneously opening or closing the shields or closures 11.

What I claim is:—

1. A drinking fountain including nozzles disposed to discharge water in streams converging to produce a solid body of water, shields movably supported by said nozzles, and means associated with said shields and including a valve for controlling the discharge of water from said nozzles.

2. A drinking fountain comprising nozzles arranged to discharge water to produce a momentarily suspended body of water, shields movable relatively to said nozzles, and a valve controlling the supply of water to said nozzles and adapted to actuate said shields.

3. A drinking fountain comprising nozzles arranged to discharge water to a central point, shields movable relatively to said nozzles and adapted to cause the water to wash the ends of said nozzles, a valve controlling the supply of water to said nozzles, and means connected to said shields and actuated by the opening and closing of said valve to move said shields.

4. A drinking fountain comprising nozzles arranged to discharge water to a central point, shields movable relatively to said nozzles and adapted to cause the water to wash the ends of said nozzles, a valve controlling the supply of water to said nozzles, means connected to said shields and ac-

tuated by the opening and closing of said valve to move said shields, and a pressure regulator in communication with said nozzles and controlling the pressure of water supplied to said nozzles.

5. A drinking fountain including a plurality of water outlets to discharge water to produce a momentarily suspended body of water, shields movable relatively to said outlets for closing them, and valvular means controlling the supply of water through said outlets and actuating the shields when the valve is operated.

6. A drinking fountain comprising a plurality of water discharging elements arranged to produce converging streams of water to provide a momentarily suspended body of water, a shield pivotally connected to each of said elements and capable of being shifted to open and close its respective element and further adapted to cause the water to clean its respective element, said elements adapted to connect with the water supply, means for controlling the supply, 20 and operating means for said shields actuated from said controlling means.

7. A drinking fountain comprising a plurality of water discharging elements arranged to produce converging streams of water to provide a momentarily suspended body of water, shields for said elements, each capable of being shifted to close its respective element and further adapted to cause the water to clean its respective element, means for controlling the water supply to said elements, and operating means for said shields actuated from said controlling means.

8. A drinking fountain including a number of water discharging outlets so arranged that they discharge water in streams that converge to produce a momentarily suspended body of water suitable for drinking purposes, and shields movable relatively to said outlets for closing them, and common means adapted to actuate said shields.

9. A drinking fountain including a number of water discharging outlets so arranged that they discharge water in streams that converge to produce a momentarily suspended body of water suitable for drinking purposes, shields movable relatively to said outlets, and common means adapted to actuate said shields.

55. 10. A drinking fountain comprising means to provide water outlets disposed to discharge water in streams converging to produce a solid body of water, a shield associated with each outlet for closing it, means for shifting said shields simultaneously away from the discharging ends of the outlets, and valvular means for controlling the discharge of water through said outlets.

11. A drinking fountain comprising

means to provide water outlets disposed to 65 discharge water in streams converging to provide a solid body of water, shields associated with said outlets, valvular means for controlling the discharge of water through said outlets, and means whereby said shields 70 are simultaneously shifted away from the discharging ends of the outlets when the valvular means is opened and shifted to close the outlets simultaneously with the closing of the valvular means.

75. 12. A drinking fountain comprising water outlets disposed to discharge water in streams converging to produce a solid body of water, shields associated with said outlets for closing them, valvular means for controlling the discharge of water through said outlets, and operative connections between said shields and said means whereby the shields are operated simultaneously with the operation of said valvular means and 80 whereby the shields can be positioned in close proximity to the discharging ends of said outlets so that the water passing from the outlets will impact against the shields and be thrown back to cleanse the discharg- 85 ing ends of the outlets.

90. 13. A drinking fountain comprising means to provide water outlets disposed to discharge water in stream converging to produce a solid body of water, shields associated with said outlets for closing them and further adapted to throw back the water passing through the outlets to cleanse the discharging ends of the outlets, and means arranged exteriorly of the outlet and operated simultaneously with the opening and closing of a water supply, for shifting the shields away from and toward the outlets.

95. 14. The combination with a water supply, and means for controlling the same, of water 105 discharging elements in connection with said controlling means for discharging water in converging streams, a pressure regulator interposed between said elements and controlling means, and shields associated with said elements and operable in unison with said controlling means.

10. 15. A drinking fountain comprising a water discharging element, means capable of being adjusted to a position in close 115 proximity to the outlet end of said discharging element as the water is discharging whereby the water will impact against said means and be thrown back to cleanse the discharging end of said element, means 120 for holding said water impacting means in the position to which it has been adjusted and for producing relative movement between said impacting means and said water discharging element, said movement being 125 such that the inner face of said impacting means simultaneously moves across the path of discharge from said water discharging

element and recedes from the discharge end of said water discharging element in the direction of discharge.

16. A drinking fountain comprising a water discharging element, means capable of being positioned in close proximity to the outlet end of said discharging element while the water is discharging whereby the water will impact against said means and be thrown back to cleanse the discharging end of said element, a valvular element for controlling the supply of water to said discharging element, and interdependent connections between said means and said valvular element for controlling the position of said means during all movements of the valvular element and for producing relative movement between said impacting means and said water discharging element, said movement being such that the inner face of said impacting means simultaneously moves across the path of discharge from said water discharging element and recedes from the discharge end of said water discharging element in the direction of discharge.

17. A drinking fountain comprising a water discharging element, a shield associated therewith, a valvular element for controlling the supply of water to said discharging element, and interdependent connection between said valvular element and shield whereby the shield is shifted away from the water discharging element to open the same simultaneously with the opening of the valvular element and shifted toward and against the water discharging element to close the same simultaneously with the closing movement of the valvular element, said connections being such that the movements of the shield is had directly from the valvular element and for producing relative movement between said impacting means and said water discharging element, said movement being such that the inner face of said impacting means simultaneously moves across the path of discharge from said water discharging element and recedes from the discharge end of said water discharging element in the direction of discharge.

50 18. A drinking fountain comprising water

outlets disposed to discharge water in streams converging to produce a solid body of water, shields associated with said outlets for closing them, valvular means for controlling the discharge of water through said outlets, and means operated by said valvular means for positioning said shields in close proximity to the discharging ends of the outlets whereby the water passing through the outlets will impact against the shields and be thrown back to cleanse the discharging ends of the outlets.

19. A drinking fountain including a water discharging element, a valvular element for controlling the supply of water to said discharging element, a shield associated with and connected to said discharging element, and means operated by said valvular element for adjusting the position of said shield with respect to the discharging element, said means operating said shield in unison with the opening and closing of the valvular element, said means connected directly to said valvular element and for producing relative movement between said impacting means and said water discharging element, said movement being such that the inner face of said impacting means simultaneously moves across the path of discharge from said water discharging element and recedes from the discharge end of said water discharging element in the direction of discharge.

20. A drinking fountain comprising water outlets disposed to discharge water in streams converging to produce a solid body of water, shields associated with said outlets for closing them, and common manually operable means for positioning said shields in close proximity to the discharging end of the outlets whereby the water passing through the outlets will impact against the shields and be thrown back to cleanse the discharging ends of the outlets.

In testimony whereof I affix my signature in the presence of two witnesses.

BENNETT KAMINSKY.
